UNITED STATES PATENT OFFICE

JOSEPH SILVERMAN, OF CHICAGO, ILLINOIS

KNEELING BENCH

Application filed November 4, 1929. Serial No. 404,588.

This invention relates to kneeling benches, such as those commonly used in religious and other ceremonials.

In different forms of religious worship, and in other ceremonials of religious import, it is usual to provide some sort of bench or other support upon which the participant may kneel, and these benches usually provide a cushion or other support, not only one upon which the participant may kneel but also one upon which he may rest his arms.

Heretofore such benches have been a part of the permanent furniture of the church or other organization, and the benches have, therefore, been rather heavy and not easily adapted to be moved from place to place.

Occasionally, however, there arises situations where it is desirable to temporarily set up kneeling benches to be used for only a comparatively short time. For example, at wakes or funeral ceremonies it may be desirable to provide kneeling benches for temporary use. Sometimes at marriages it is desirable or necessary to provide kneeling benches for use during certain portions of the ceremony. Also, certain church services sometimes require the addition of temporary kneeling benches to the regular altar equipment, such as, for example, requiem mass where the altar services are considerably augmented.

It is one object, therefore, of my invention to provide a kneeling bench adapted particularly for temporary use and which is so arranged and constructed that it may be folded so as to occupy a small space when not in use. Another object of my invention is to provide, in a folding or collapsible kneeling bench, structure adapting the bench when extended into operative position to be sturdy and rigid.

A still further object of my invention is the provision of a kneeling bench wherein the collapsible parts are adapted to be folded in between the frame members so that the bench may occupy the minimum of space. A further object of my invention is to provide means for limiting the folding movement of the collapsible parts so that the bench, when collapsed into inoperative position, is not likely to accidentally become extended so as

to thereby become difficult to stack or store away.

Other objects and advantages of my invention will be apparent to those skilled in the art after a consideration of the following detailed description, taken in conjunction with the accompanying drawings, in which:

Fig. 1 is a front elevation showing the kneeling bench in extended and operative position;

Fig. 2 is a cross section taken approximately on the line 2—2 of Fig. 1 showing, however, certain parts in elevation;

Fig. 3 is a front elevation showing the kneeling bench upright but in folded or collapsed position; and

Fig. 4 is an enlarged side elevation showing certain parts as broken away.

Referring to the drawings, the reference numeral 1 indicates the frame of my kneeling bench and which is seen to comprise the two uprights 2 and 3 and the top horizontal member 4. The frame is reinforced and strengthened by the transverse members 5, 6, and 7, secured to the upright members 2 and 3 as by riveting or welding or the like. These frame members are preferably formed of sheet metal of the proper gauge having rolled edges, as shown in Figures 2 and 4. The bottoms of the upright members 2 and 3 are provided with foot portions in the form of rubber tips 9 which serve, not only to prevent the frame from slipping but also to prevent the bench from marring any surface upon which it may be placed.

The arm rest 12 includes a substantially rectangular frame 13 pivoted to the frame 1 by means of hinges 14, and the hinges 14 may be secured to the frame 1 in any desired manner, as by screws 15. The padded member 16 of the arm rest 12 is provided with a base 17 which is fastened to the rectangular frame 13 by means of clips 18. The clips 18 may be welded or otherwise secured to the frame 13 and they may be secured to the base 17 by means of screws 19.

The arm rest 12 is adapted to be held in extended and operative position by means of a toggle brace 21, the component members of which are pivoted respectively to the 100

frame 13 and to the frame 1, as shown best in Fig. 2. The adjacent ends of the parts 22 and 23 are pivoted together, as at 25, and each adjacent end is provided with an abutment 27 struck from each of the parts and in such a manner that these abutments 27 engage one another just beyond the dead center position of the toggle brace 21. The toggle brace 21 is adapted to rigidly hold the arm rest 12 in extended position, as shown in Figure 2, but when the toggle is broken the parts 22 and 23 break upwardly to allow the arm rest 12 to pivot downwardly to the position shown in Fig. 4. It will be noted that in its collapsed position the rest 12 lies substantially between the upright members 2 and 3. The transverse member 5 acts as means to limit the downward pivoting of the arm rest 12.

The knee rest 30 is formed quite similarly to the arm rest 12 and is seen to consist of a padded cushion-like member 31 secured, as by clips 33, to the frame 35 in substantially the same manner that the padded member 16 is secured to the rectangular frame 13, described above. The frame 35 of the knee rest 30 is rectangular in shape, like the frame 13 of the arm rest 12, but is somewhat wider so as to space the member 31 a proper distance from the frame 1. The frame 35 is pivoted to the frame 1 preferably by means of headed pivots 36, the frame 35 being spaced the proper distance from the upright members 2 and 3 by means of washers 37, see Fig. 3.

The frame 35, like the frame 13, is interconnected with the frame 1 by means of toggle brace means 40, the component parts 41 and 42 of which are respectively pivoted to the frame 1 and to the frame 35. The toggle means 40 is adapted to be broken so as to allow the knee rest 30 to be swung upwardly to a collapsed position, substantially between the upright members 2 and 3, as shown in Fig. 4. The transverse member 6 serves to limit the upward pivoting of the knee rest 30, as is clear from Fig. 4.

In order to support the bench in an upright position I provide the knee rest 30 with a pivoted bracket or supporting member 45 having curved foot members 46 and 47. The ends of the supporting member 45 are pivoted to the frame 35 by means of pivots 50 passing through the frame 35 and the member 45. The member 45 is properly spaced relative to the frame 35 by means of washers 51.

The supporting member 45 is also adapted to be collapsed and to take a position within the frame member 35 adjacent the cushion member 31, see Fig. 3. The means I have provided for maintaining the supporting member 45 in extended position comprises a toggle brace 55 of substantially the same form as, and operative in the same manner

as, the toggle braces 21 and 42 which have been described in detail above. When the toggle brace 55 is broken inwardly, see Fig. 2, the supporting member 45 may be swung upwardly, relative to the frame 35, so that when the knee rest 30 is folded into collapsed position the whole occupies a relatively small space between the upright members 2 and 3.

While I have shown the frame members 1, 13 and 35 as being formed of sheet metal, whereby great lightness and strength is obtained, it is obvious that these frames may be formed of wood or any other desired and suitable material.

The principal and essential aspect of the present invention is the collapsibility of a structure of this sort so that the required number of kneeling benches may be easily transported and set up wherever they may be required and may at the same time be conveniently folded and compactly stacked away when not in use.

While I have described in connection with the accompanying drawings the specific form in which I prefer to embody my invention, it is to be understood that the invention is not to be limited to the specific means which I have herein shown and described, and that, in fact, widely different means may be employed in the practice of the broader aspects of my invention.

What I claim, therefore, and desire to secure by Letters Patent is:

1. A collapsible kneeling bench comprising a frame including transverse bracing members, an arm rest and a knee rest pivoted to said frame, separate means connected to the frame and to the arm rest and the knee rest respectively to hold the rests in extended position, said connecting means being operable to permit said rests to be swung to inoperative position inwardly toward the frame, said transverse frame members limiting the swinging of said rests past an aligned position with respect to said frame.

2. A collapsible kneeling bench comprising a frame having foot portions, an arm rest and a knee rest including frame and padded supports mounted thereon, said rests being pivoted to said frame, means connecting the arm rest and the knee rest to the frame to hold the rests in extended position, said connecting means being operable to permit said rests to be swung to inoperative position against the frame, and a collapsible supporting member carried by the frame of one of said rests and adapted to cooperate with said foot portions to form supports for the bench to maintain the bench in upright position when said rests are extended.

3. A collapsible kneeling bench comprising a frame including side members, an arm rest and a knee rest, each comprising a frame and a padded support secured thereto, means

pivoting each of said last mentioned frames to the frame of the bench, toggle means connecting each of said rest frames to the frame of the bench and operative at will to independently hold the respective rests in extended position and to allow them to be collapsed to a position adjacent the frame of the bench, and transverse members on the frame to limit the pivotal movement of said frames in one direction.

4. A collapsible kneeling bench comprising a frame including upright members, an arm rest and a knee rest, each comprising a frame and a padded support secured thereto, means pivoting each of said last mentioned frames to the frame of the bench, toggle means connecting each of said rest frames to the frame of the bench and operative at will to independently hold the respective rests in extended position and to allow them to be collapsed to a position adjacent the frame of the bench, transverse members on the frame to limit the pivotal movement of said frames in one direction, and collapsible means on the frame of the knee rest to cooperate with the frame of the bench to support the latter.

5. A collapsible kneeling bench comprising a frame having foot portions, an arm rest and a knee rest comprising frames and padded supports, each of said rests being pivoted to said frame, means connecting the arm rest and the knee rest to the frame to hold the rests in extended position, said connecting means being operable to permit said rests to be swung to inoperative position against the frame, means carried on the frame of one of said rests and adapted to cooperate with said foot portion to form supports for the bench to maintain the bench upright when said rests are extended, and means connected between the frame of said last mentioned rest and said support-forming means to hold said means in supporting position relative to said frame.

6. A collapsible kneeling bench comprising a frame including side members and an intermediate transverse member, an arm rest, a knee rest, means pivoting said arm rest about said transverse member, means pivoting said knee rest between said side members, said pivoting means permitting said rests to swing outwardly of the frame away from each other when extended into operative position, and toggle means holding said rests in extended position.

7. A collapsible kneeling bench comprising a frame including parallel side members and an intermediate transverse member, an arm rest, a knee rest, means pivoting said arm rest about said transverse member, means pivoting said knee rest between said side members, said pivoting means permitting said rests to swing outwardly of the frame away from each other when extended into

operative position, and means rigidly securing said rests in extended position.

In witness whereof, I hereunto subscribe my name this 26th day of October, 1929.
